FOOD SERVICE CARRIER

H. George Skaller, Flushing, N. Y.

Application March 25, 1957, Serial No. 45,419

Term of patent 14 years

(Cl. D14—3)

FIG. 1.

FIG. 2.

FIG. 4.

FIG. 3.

Fig. 1 is a perspective view of a food service carrier embodying my new design;

Fig. 2 is a side elevational view thereof;

Fig. 3 is a side elevational view of the side opposite to that shown in Fig. 2; and

Fig. 4 is a rear elevational view thereof.

I claim:

The ornamental design for a food service carrier, substantially as shown.
